BROADCASTING WITH REDUCED BAND WIDTH

Nicolaas Koomans, The Hague, Netherlands

Application December 14, 1935, Serial No. 54,359½
In the Netherlands December 14, 1934

5 Claims. (Cl. 250—17)

The invention relates to a method of broadcasting and to a transmitter in which a modulated wave is radiated, said wave comprising a carrier and two side bands, one of said side bands being complete and the other containing only components corresponding to low notes.

According to the invention such a wave is obtained by dividing the voice-current low frequency into two parts, one of which comprises only high notes, the other part containing the remaining low notes. The low notes are then modulated according to the usual two-side-band method, and the high notes according to the single-side-band method, the carrier frequency being the same in both cases. Subsequently the products of modulation are added.

The invention is the outcome of attempts to reduce the actual over-crowding in the ether.

A well-known proposal to obtain such a reduction is the suppression of one of the two side bands in a wave modulated according to the usual two-side-band method. The following difficulties are mainly associated with this proposal:

First it is difficult to include the low notes to the correct extent in the modulation and secondly distortion products in the shape of higher harmonics occur in the case of linear rectification at the receiving end, this defect increasing as the depth of modulation is increased. Low notes are especially troublesome in this respect; in the first place because they are as a rule deeply modulated on the carrier, and secondly because the higher harmonics of these components fall mostly within the audible range.

As a rule the higher notes are much less strongly modulated and for the most part these higher notes determine the timbre.

The present invention meets these difficulties by utilizing a system ensuring a considerable reduction in the necessary band-width, but with which at the same time a good quality of communication is possible. A feature of the method of the invention used in this system is that in addition to the carrier wave one side band is sent out completely and the other side band only insofar as the components represent low notes.

In other words the low notes of the audio-frequency spectrum to be radiated will be represented in both side bands, and the high notes in one side band only.

In this way the distortionless reception of low notes in a linearly detecting receiver is ensured.

As the low-note energy is distributed over the two side bands and the high-note energy is concentrated in a single side band, the ratio of the

high and the low note modulation must be chosen correctly with a view to the type of demodulation to be used in the receivers to be associated with the broadcasting station. If reception is to be effected on normal linear detectors it will be necessary to effect a correct choice of the said ratio; this may be done experimentally. A requirement to be expected is that the strength of the single side band containing the high notes should be about double that of each of the side bands containing the low notes, as these are added in the detection.

A particular way of carrying into effect the method according to this invention is to split the audio-frequencies in two ranges, the one range only containing low notes and the other containing the remaining high notes. The first range is modulated in the usual two-side band manner, and the second range according to a single-side band system. The low notes may thus be modulated in a usual manner, which does not give rise to difficulties, and the high notes may be directly modulated on a carrier of comparatively high frequency without consequent difficulties relating to the filtering of one side band from the resulting mixture. The said high-frequency carrier may be intermediate or alternatively may itself be the carrier to be radiated, dependent on circumstances, such as the wave length on which the modulation is effected and on the frequency of separation of the high and low ranges.

By the possibility of choosing at a high value the carrier on which the high notes are modulated, any difficulty due to the appearance of higher harmonics of the modulating notes in the modulation is avoided.

It is advisable to arrange suitably for the two-side-band modulation of the low notes to be flat, so that the single-side-band modulated high notes may be added without carrier wave; in other words the surplus of carrier in the two-side-band modulated part serves as the carrier in the single-side-band modulation. The depth of modulation will be so chosen that a sufficient carrier amplitude is obtained for the entire wave; this carrier will have the required phase.

As it may be difficult to effect a separation into a high and a low region in an abrupt manner and the line of separation will thus in general be oblique, it is desirable to take this effect into account in the modulating process and to secure a corrective overlap of the two obliquely limited note components.

The invention will now be described with particular reference to the accompanying drawing, in which:

Fig. 1 represents a frequency scale of a wave form as emitted by a transmitter according to the invention.

Fig. 2 shows a diagram of a transmitter according to the invention.

In Fig. 1 the abscissae represent frequencies and the ordinates amplitudes. The location of the carrier frequency is indicated. This frequency is modulated in the example with audio-frequency currents comprising frequencies from 0-7 k. c. As shown the audio-frequencies from 0-2 k. c. are modulated on the carrier by the two-side-band method and the audio-frequencies from 2-7 k. c. are modulated by the single-side-band method.

Fig. 2 shows a diagram of a transmitter adapted to realize the wave form shown in Fig. 1.

The transmitter of Fig. 2 modulates in two stages, the first carrier frequency being 15 k. c. and the second 145 k. c.; modulation is by an audio-frequency band extending from 0-7 k. c. in the manner shown in Fig. 1, so that the resulting wave comprises frequencies extending from $15+145-2$ k. c. to $15+145+7$ k. c., that is from 158-167 k. c., the carrier frequency being 160 k. c. As shown the audio-frequencies entering at 1 are amplified in two paralleled amplifiers 2 and 3, the amplifier 2 being provided with a band-pass filter from 0-2 k. c. and amplifier 3 having a band-pass filter from 2-7 k. c. The output from amplifier 2 is modulated in modulator 4, the output from amplifier 3 in modulator 5, each of these modulators being supplied by carrier from generator 6 at 15 k. c.; the modulators are provided with output band filters as shown, whereby the output from modulator 4 comprises two side-bands and that from modulator 5 only a single side band, as indicated in the small diagrams below the filters. The outputs from modulators 4 and 5 are amplified in amplifiers 8 and 9, the plate circuits of which are paralleled. Through the volume control 10 the outputs from amplifiers 8 and 9 are supplied to the final modulator 11, supplied from the generator 7 with carrier at 145 k. c. The output from modulator 11 is led through a filter 12 and emitted, the frequency spectra of this emission being shown again below the filter.

I claim:

1. Method of broadcasting comprising the steps of amplifying a section of the audio-band to be modulated, this section comprising lower frequencies, and separately amplifying the remaining part of the audio-band comprising higher frequencies, modulating the first-named section in a two-side band modulator and the second section in a single-side-band modulator, amplifying the modulation products to different amplitudes, and adding the modulation products. 10

2. Method of broadcasting comprising modulating a section of the audio-band containing only notes below a given frequency in a first modulator on a given carrier frequency and the remaining section of the audio-band on the same carrier in a second modulator, the first modulator being a two-side band modulator and the second modulator a single side band modulator, differently amplifying the modulation products, and radiating the said products. 15

3. Method of broadcasting comprising modulating a section of the audio-band containing only notes below a given frequency in a first modulator on a low carrier frequency and the remaining section of the audio-band on the same carrier in a second modulator, the first modulator being a two-side band modulator and the second modulator a single side band modulator, differently amplifying the modulation products, 20 modulating the products of modulation of the first and second modulators on a third modulator operating at a higher carrier frequency, and radiating the products of modulation of this modulator. 25

4. Broadcast transmitter, comprising a path for low audio frequencies and a path for the remaining audio-frequencies, the first-mentioned path including a double side-band modulator for modulating the low audio-frequencies on a carrier, the second path including a single side-band modulator for modulating the remaining frequencies on a carrier of the same frequency, means for differently amplifying the modulation products and means for radiating the products of 40 modulation together. 45

5. A method of broadcasting as set forth in claim 2, additionally characterized in that the single side-band modulator is of the suppressed carrier type. 50
